UNITED STATES PATENT OFFICE.

LOUIS W. GEEREKEY, OF DOUGLAS, ARIZONA.

CHILD'S CRIB OR BERTH ATTACHMENT FOR RAILROAD-CARS.

1,090,705.

Specification of Letters Patent. Patented Mar. 17, 1914.

Application filed January 21, 1910, Serial No. 539,299. Renewed May 12, 1913. Serial No. 767,191.

To all whom it may concern:

Be it known that I, LOUIS W. GEEREKEY, a citizen of the United States, residing at Douglas, in the county of Cochise and State of Arizona, have invented a Child's Crib or Berth Attachment for Railroad-Cars, of which the following is a specification.

This invention is an improvement over that disclosed in my Patent No. 1,055,897, dated March 11, 1913, and it relates to an improvement in the means for securing a crib to horizontal rails applied to the inner side of a railway carriage.

The invention is hereinafter described and illustrated in the accompanying drawings.

In the accompanying drawings, which form a part of this specification: Figure 1 is a cross section of a car showing the application of my invention thereto. Fig. 2 is a side elevation, showing the movable carriage and crib or berth which is adjustably supported thereon. Fig. 3 is a side elevation, partly in section, of the carriage or support for the crib or berth, the same being detached from the supports attached to the car. Fig. 4 is a part plan and sectional view through the carriage. Figs. 5 and 6 are respectively sections and side views of the crib or berth.

Like numerals of reference indicate like parts in all the figures of the drawings.

In carrying out my invention I attach to the inner wall at either side of the car three horizontally disposed rails 1, 2, and 3, running preferably the full length of the car, and spaced apart, as shown in Fig. 1. These rails are made of metal, and may be comparatively light so as to not disfigure the appearance of the car, the upper and intermediate rails having oppositely disposed guide-flanges 1^a and 2^a, respectively, which overlap the wheels of the carriage, hereinafter described, so as to maintain said carriage in vertical position; while the lower rail 3 is provided in its upper side with a longitudinal groove, 3^a, serving as a guide for the lower end of the carriage. The intermediate rail 2 is provided with an upwardly-projecting flange 4 having notches 5, and similar notches 6, are formed in the outer edge of the lower rail 3, said notches coöoperating with catches on the carriage for holding the latter in locked position.

The carriage consists of a vertical back-plate or board 7, having formed on or se-

cured to the rear side thereof upper and lower wheel-boxes 8 and 9, respectively, similar to the ordinary form of sliding-door hanger, said boxes each having a set of two wheels 10, 10. These two sets of wheels are spaced apart corresponding to the distance between the supporting-rails 1 and 2 on the car, and so that the upper set of wheels may travel upon the rail 1, and the lower set along the underside of rail 2, while the lower edge of the back-plate slides in the groove 3^a of the rail 3. At the lower end of the back-plate of the carriage is a metal angle-plate 11, which overlaps the front of the rail 3, and at this end of said back-plate is also a sliding-catch 12 which is adapted to engage any one of the notches 6 in said lower rail, said catch serving to hold the carriage firmly to any position along the rails to which it may be moved, for instance in front of any one of the car seats. A similar sliding-catch 13 is mounted on the rear side of the back-plate for engagement with the notches 5 in the intermediate rail 2, so as to more securely hold the carriage.

Upon the front of the back-plate 7 of the carriage is a vertical guide-rail 14, having a T-shaped groove 15 therein and notches 16 along one edge, and alongside of this guide-rail is a vertical tube or housing 17 for a counterbalancing weight, hereinafter referred to.

For the purpose of moving the carriage along the rails a handle 18 is secured to or formed on the carriage, preferably at one side of the housing 17, as shown.

At the upper end of the back-plate 7, above the guide-rail and housing is a pulley 19, journaled in a bearing-bracket 20, and over this pulley passes a cord 21, one end of which passes down into the groove 15 in the guide-rail 14 for attachment to a bracket-arm 22 forming part of the crib or berth, while the other end passes down in the housing or tube 17 and is attached to a counterbalancing weight 23 sliding in said tube or housing. The inner end of the sliding-bracket 22 is T-shaped in cross section to fit slidably in the correspondingly-shaped groove in the guide-rail 14 of the carriage, and as an additional support or guide for this bracket an angle-plate 23' is secured to one side thereof and adapted to bear against the plain edge of said rail; and for the purpose of supporting this bracket at any desired elevation on the carriage the former is

provided with a sliding-catch 24, adapted to engage any one of the notches 16.

At the outer end of the slidable supporting bracket 22 is a bowl-shaped socket 25, 5 to receive a corresponding member 26 on a turn-table 27, to which latter the crib or berth is secured. In the present instance the crib or berth comprises three sections, a center section 28, a head section 29, and a 10 foot section 30, the head and foot sections being suitably hinged to the said center section. The head and foot sections are connected at each side by means of a jointed rod comprising sections 31 and 32, the rod 15 31 being secured along the edge of the head section while the rod 32 is pivoted to the lower end of the foot section, and the meeting ends of said rods overlap and are connected by means of a clamping-bolt 33. As 20 will be seen, therefore, when the head section is moved up or down a corresponding movement, though in the opposite direction, will be imparted to the foot section, and when these sections are adjusted to different 25 positions they are held by simply tightening the nut 33' on the bolt. The center section may be and preferably is provided with

raised sides 34, and the several parts of the crib or berth are suitably upholstered.

Having thus described my invention, I 30 claim:

In a crib attachment for railway cars, the combination with a car body, of three horizontal rails extending along the side of the car interiorly and spaced apart vertically, the upper rail having an upwardly projecting flange, the middle rail being T-shaped in cross section, and the lower rail having a lengthwise groove, of a crib carrier comprising a vertical back plate having two wheels at the top that run on said upper rail and two middle wheels that run underneath the middle rail, the lower end of the said back plate being slidable in the grooved bottom rail, and slidable catches attached to the back plate and adapted to enter notches in the middle and lower rails, as described.

Signed at Douglas, Ariz., Jan. 7th, 1910.

LOUIS W. GEEREKEY.
